UNITED STATES PATENT OFFICE.

HENRY A. STENGER, OF COWELL, CALIFORNIA.

SELF-OILING PUMP-HEAD.

1,134,929.

Specification of Letters Patent.

Patented Apr. 6, 1915.

Application filed December 13, 1913. Serial No. 866,541.

To all whom it may concern:

Be it known that I, HENRY A. STENGER, a citizen of the United States, residing at Cowell, in the county of Contra Costa and State of California, have invented certain new and useful Improvements in Self-Oiling Pump-Heads, of which the following is a specification.

The primary object of this invention is to

10 provide power transmitting mechanism for pumps arranged in the most compact form for communicating reciprocatory movement to the pump rod or similar operating member.

15 One of the essential features of my invention is the formation of the pump head comprising this mechanism so as to insure the proper lubrication of the operating elements with the least amount of attention and to 20 this end said elements are disposed in a bath of lubricant making necessary the replenishment of the supply thereof only at lengthy intervals.

25 More specifically speaking my device comprehends the provision of a driving member having eccentric means formed thereon with which a lifting member co-operates, an eccentric rod connected to said lifting member, and means co-operating with the eccentric 30 rod whereby to cause reciprocation of said rod upon actuation of the lifting member by the driving member aforesaid.

With the above and other objects in view, this invention consists in the construction, 35 combination and arrangement of parts all as hereinafter more fully described, claimed and illustrated in the accompanying drawings, wherein:

Figure 1 is a side elevation of a pump head constructed in accordance with my invention and showing in dotted lines the co-operation of the lifting member with the driving means therefor; Fig. 2 is a vertical section view taken about on the line 2-2 of Fig. 1; Fig. 3 is a side elevation of my pump head taken from the side opposite that shown in Fig. 1; Fig. 4 is a horizontal section view taken through the cover member for the pump head showing more clearly

the construction of the guiding means for 50 the eccentric rod; and Fig. 5 is a vertical sectional view through said cover member.

Specifically describing my invention and referring to the drawings, the numeral 1 designates a casting which is hollow in construction to form a casing, and 2 the base 55 for the pump head.

The numeral 3 represents the cover for the casing 1, which element is shown most clearly in Figs. 3, 4 and 5, respectively, of 60 the drawings, and 4 the pump rod which is to be operated by the power transmitting mechanism more specifically described hereinafter. The rod 4 as shown in the drawings is the type of rod usually employed in 65 pumps and windmills to which reciprocatory motion is usually imparted. Within the casing 1 is disposed a driving member or disk 5 to the outer periphery of which is secured the gear element 6, as by means of 70 fastening members or bolts 7. The gear member 6 meshes with a worm 8 on the driving shaft 9 connected with any convenient source of power such as a motor, which forming no part of my invention, is 75 not illustrated. The shaft 9 is provided with suitable ball bearings 10 and may be readily reversed in its connection with the driving gear 6 by the removal of the sectional caps 11 and 11' suitably secured to 80 the upper side portion of the casing 1 by fastening members 12. The function of the reversibility of this shaft will be evident to those skilled in the art to which this invention refers, it being necessary at times to 85 drive the mechanism from different sides of the pump head. The disk 5 is formed on one face with a laterally projecting trun- 90 nion 13 journaled centrally of the casing 1 in the bearing 14 while on the opposite side 95 of the disk are provided projecting laterally spaced flanges 15 formed eccentric to the axis of said disk. The flanges, as will be seen from Figs. 1 and 2, form a groove 16 and in this groove is disposed a lifting mem- 95 ber or ring 17 formed with a projecting stud 18. Pivottally connected to the stud 18 is provided an eccentric rod 19 which is adapt-

ed to move vertically in the groove 20 of the cover 3, and at the upper extremity said rod 19 is connected to the pump rod 4 by the connecting block 21. As clearly shown in Figs. 2 and 5 the cover plate 3 is formed at its upper and lower portions with apertured projections 22 in which the pump rod 4 is adapted to reciprocate.

As hereinbefore stated one of the advantageous features of my construction is the formation of the casing 1 or pump head so as to contain a lubricant which is supplied to the hollow interior of said casing by the removal of a plug 23, and said lubricant may be withdrawn from the casing 1 through the instrumentality of the pet-cock 24 disposed at the lowermost portion of said casing. The trunnion 13 on the disk 5 is preferably of hollow formation so as to provide a chamber 25 into which the lubricant will pass from the casing 1 insuring in this manner that the bearing 14 will be properly lubricated at all times. The several moving parts within the casing 1 will operate in the lubricant which fills said casing and the reciprocation of the eccentric rod 19 will cause the feeding of the lubricant the entire length of the groove 20 in the cover member for said casing, and this cover member about the top portion of the groove is reamed out as shown most clearly in Fig. 5 of the drawings and indicated by the numeral 26. An oil groove 27 leads from this point to the upper apertured projection 22 so that the pump rod 4 is effectively lubricated at this point by the surplus oil working up the rod 19.

It will be obvious from the foregoing that the mechanism may be driven at any suitable speed and any desired amount of reciprocatory movement may be imparted to a pump rod by the proper proportioning of the parts of my invention connected therewith. The driving shaft driven from a convenient source of power causes the disk 5 through the instrumentality of the gear member 6 to rotate about the axis of said disk, and the lifting member 17 disposed in the groove 16 gradually moves around in said groove lifting the eccentric rod 19 which is guided by the cover 3 so as to cause said rod to reciprocate and impart similar motion to pump rod 4. It will be apparent that such reciprocal motion of the eccentric rod 19 is permitted by the pivotal connection of the same on the stud 18 carried by the lifting ring, said stud moving in a true vertical plane at right angles to the axis of rotation of disk 5.

Having thus described the invention what is claimed as new is:

1. A pump head comprising a casing, a driving disk journaled in said casing and having an eccentric groove formed on one face of the same, a gear member removably

secured to the periphery of said disk, driving means for rotating said disk, a lifting ring disposed in the groove of said disk and having a projection extending therefrom, an eccentric rod pivotally connected to the projection, and a cover for said casing having a groove formed therein in which said eccentric rod is adapted to reciprocate whereby to maintain the said rod in rigid operative position during actuation thereof. 75

2. The combination with a pump rod, of a pump head for operating the same, a casing, a cover for said casing, an eccentric rod in the casing and connected to the pump rod exteriorly thereof, said cover being 80 formed interiorly with guide means for the eccentric rod and exteriorly with similar means for the pump rod, and driving mechanism disposed in said casing and connected to the eccentric rod whereby to impart reciprocatory motion to the eccentric pump rods. 85

3. A pump head comprising a hollow casing for containing a lubricant, a cover therefor, a driving disk having a trunnion projecting laterally from one face of the same and having its bearing in said casing, a gear member secured to the disk, a driving shaft operatively connected to said gear member, the disk aforesaid being provided with 95 spaced flanges on its face opposite the trunnion aforesaid whereby to form a groove eccentric to the axis of said disk, a lifting ring mounted for movement in said groove, 100 a stud projecting from said ring, and an eccentric rod pivotally connected to the stud and co-operating with the cover for said casing whereby said rod is adapted to reciprocate upon actuation by the lifting ring. 105

4. The combination with a pump rod, of a pump head for operating the same comprising a casing, a driving member, journaled in said casing, a cover for closing said casing having guide members for the pump rod, a rod adapted to positively engage with the cover for reciprocal movement thereof and connected with the driving member, a shaft extending into said casing for operating the driving member, and a removable cap for said casing whereby to permit reversal of the driving shaft. 110 115

5. The combination with a pump rod, of a pump head comprising a hollow casing for containing a lubricant, a cover therefor, a driving disk having a trunnion projecting laterally from one face of the same and having its bearing in said casing, a rim gear member secured to the disk, a driving shaft operatively connected to said gear member, the disk aforesaid being provided with 120 spaced flanges on its face opposite the trunnion aforesaid whereby to form a groove eccentric to the axis of said disk, a lifting ring mounted for movement in said groove, 125 a stud projecting from said ring, an eccen-

tric rod pivotally connected to the stud and coöperating with the cover for said casing whereby said rod is adapted to reciprocate upon actuation by the lifting ring, the cover aforesaid having externally apertured projections through which the pump rod extends and internal spaced flanges forming a guide groove for the eccentric rod, and a

connecting member connecting the eccentric rod with said pump rod.

10

In testimony whereof I affix my signature in presence of two witnesses.

HENRY A. STENGER.
